KEY HOLDER

Arthur H. Levesque, North Attleboro, Mass., assignor to R. F. Simmons Company, Attleboro, Mass., a partnership

Application January 3, 1945, Serial No. 571,132

6 Claims. (Cl. 70—459)

This invention relates to an improved key-holder or "key-keep," as it is sometimes called, for retaining a collection of keys in convenient form for carrying on the person.

One object of the invention is to provide a key-holder of small dimension and light weight for retaining a collection of keys in compact form.

Another object is to provide a key-holder of the type indicated comprising a member adapted for attachment to a suspension chain and having means for connecting the ends of a looped chain on which the keys may be strung.

Another object is to provide a key-holder of the type indicated having a central member with a fixed loop at one end for attachment to the suspension chain and a releasable loop at its opposite end for connecting the ends of the chain strung with keys.

Another object is to provide a key-holder of the type indicated having manually-operable clasping or latching means for securely fastening the releasable loop against accidental or unauthorized release from the central member.

Another object is to provide a key-holder of the type indicated which may be constructed from sheet-metal stampings and bent wire to render it economical to manufacture while being strong and durable in use and proof against release of the keys held thereby.

Further objects of the invention are set forth in the following specification which describes a preferred form of construction of the device, by way of example, as illustrated by the accompanying drawing. In the drawing:

Fig. 1 is a side view of the key-holder several times enlarged and illustrating it with a suspension chain attached at one end and a looped key-sustaining chain connected to its opposite end;

Fig. 2 is a similar enlarged view showing the latching or clasping means of the device as opened for release of the chain-holding loop-member at its end;

Fig. 3 is a similar view showing the chain-holding loop-member as released and slid outwardly from the central member of the key-holder to adapt it to be rotated for applying the looped chain thereto or removing it therefrom;

Fig. 4 is a further enlarged end view of the device;

Fig. 5 is an enlarged sectional view on line 5—5 of Fig. 1;

Fig. 6 is an enlarged sectional view on line 6—6 of Fig. 1; and

Fig. 7 is a similar enlarged sectional view show-

ing the clasp or latch of the device in open position.

The present improved key-holder comprises, in general, a relatively flat rectangular central member 3 having tubular bearings 4, 5, 6 and 7 at its opposite sides for receiving the ends of substantially U-shaped wire loop-members 9 and 10. One loop-member 9 is adapted for permanent attachment to a suspension chain 11 and the opposite loop-member 10 is for connection with the end links 12 of a chain 15 for holding the keys strung thereon.

The two tubular bearings 4 and 5 are of substantially the same length extending inwardly from the ends of the central member 3 with their inner ends spaced apart to provide an opening therebetween. The bearings 6 and 7 are connected to the bearings 4 and 5 by a relatively thin plate or web 16 having its ends cut away or recessed in arcuate contour to save metal and reduce the weight of the central member 3. The bearing 6 is somewhat shorter than the bearings 4 and 5 and the bearing 7, while of greater overall length, is cut away on the outside leaving a relatively short arcuate portion 18 joined to the central web or plate 16; this form of construction being for a purpose later explained.

The U-shaped loop-member 9 is formed by bending a length of wire in semicircular shape and continuing it in parallel legs 20 and 21. Its relatively long leg 20 is inserted through the bearing 4 and part way into the bearing 5 as indicated by dotted lines in Figs. 1, 2 and 3. The opposite leg 21 of the loop-member 9 extends for only a short distance, just sufficient for it to be supported within the end of the bearing 6. The loop-member 9 is held in this relationship permanently by forcing its legs 20 and 21 into the bearings 4, 5 and 6 or by any other suitable means such as by contracting the bearings therearound or through the use of solder. The loop-member 10 also has one long leg 22 which projects through the bearing 7 and into the bearing 6 with another shorter leg 23 adapted for insertion part way into the bearing 5. The leg 22 of the loop-member 10 is slidably mounted in the bearings 6 and 7 and also rotatable therein after its shorter leg 23 has been withdrawn from the bearing 5. Through this arrangement the loop-member 10 is adapted

50 to be rotated on the axis of its longer leg 22 into open position as indicated by dotted lines in Fig. 3, whereof the links 12 of the chain 15 may be connected therewith as shown in Fig. 1 or one end link detached therefrom.

55 For holding the loop-member 10 in closed re-

lationship and locking it against sliding movement to release its leg 23 from the bearing 5 on the member 3, I provide a manually-operable clasping means or latch 25 hingedly mounted on the longer leg 20 of the loop-member 9 between the inner ends of the bearings 4 and 5. As shown most clearly in Fig. 7, the clasping means or latch 25 is constructed from a strip of sheet-metal curled around at one end to provide a cylindrical bearing 26 encircling the leg 20 of the loop-member 9 and shaped at its opposite end with a curved hook 27 adapted to clasp around the longer leg 22 of the loop-member 10 with a snap action, see Fig. 6. The outer periphery of the hook 27 is formed with a protuberance or rib 28 adapted to be engaged by the fingernail to lift the latch 25 to free its hook 27 from engagement with the leg 22 to open the clasp and release the loop-member 10 as shown in Fig. 3. The outer surface of the clasping element or latch 25 is grooved or indented longitudinally at its center for the sake of ornamentation or it may be chased, engraved or otherwise embellished if desired.

The longer leg 22 of the releasable loop-member 10 is provided with an abutment or boss 30, formed integral therewith or fastened thereon in any suitable manner, and serving as a stop or detent to prevent the loop-member 10 from being slid outwardly when the latch is closed around this leg of the member. That is to say, the hook 27 on the clasping element or latch 25 is adapted to snap into engagement with the leg 22 of the loop-member 10 at one side of the abutment or boss 30 to lock the loop-member against sliding movement in the bearings 6 and 7. When the latch 25 is released and swung open as shown in Fig. 2 the loop-member 10 may be slid outwardly from the central member 3 until its shorter leg 23 is clear of the bearing 5 as shown in Fig. 3 and at this juncture the abutment or boss 30 will bring up against the end of the arcuate inward portion 18 of the bearing 7 which forms a stop to prevent complete release of the loop-member 10. The boss 30 also serves to limit the inward sliding movement of the loop-member 10 by engaging the end of the bearing 6 on the member 3.

In use the present improved device operates as follows: It has been stated that the loop-member 9 is fixedly secured to the central member 3 with both ends closed so that a chain 11 or other suspension means may be fastened thereto by opening an end link thereof and engaging it with the loop. To apply the keys to the holder, the clasping means or latch 25 is swung open as shown in Figs. 2 and 7 with its bearing 26 pivoting on the leg 20 of the loop-member 9 between the bearings 4 and 5. The loop-member 10 then may be drawn outwardly to the position shown in Fig. 3 and rotated on the axis of its leg 22 to open it to the position indicated by dotted lines in this view. One end link 12 of the chain 11 then can be slipped onto the free end of the loop-member 10 and after the keys have been strung on the chain the opposite link 12 may be engaged with the loop-member 10 in the same manner. The loop-member 10 is then rotated back to the position shown by full lines in Fig. 3 and its leg 22 slid into the central member 3 to engage its shorter leg 23 in the end of the bearing 5 as shown in Fig. 2. The clasping element or latch 25 is swung on its pivot and its hooked end 27 snapped over the leg 22 of the loop-member 10 between

the boss 30 and the end of the bearing 7. As the latch 25 is thus engaged around the leg 22 of the loop-member 10 abutting the boss 30 the releasable loop-member will be held securely from sliding movement in the bearings 6 and 7 so that the looped key-holding chain 15 is fastened to the device without chance of accidental disconnection therefrom. Due to the flexibility of the chain 15 the keys strung thereon will be held suspended from the device in close contact, one with another, and in compact form to avoid bulging the pocket or receptacle in which they are contained. It thus will be observed that the present invention provides an extremely neat and compact form of key-holder or key-keep adapted to be worn on a chain and carried in the pocket or to be used without a suspension chain and contained in a handbag or other receptacle.

While the improved key-holder is herein shown as embodied in a preferred form of construction it is to be understood that various modifications may be made in the structure and arrangement of its parts without departing from the spirit or scope of the invention as expressed in the accompanying claims. Therefore, without limiting myself in this respect, I claim:

1. A key-holder comprising a main member consisting in a central relatively thin sheet-metal plate provided with spaced tubular bearings extending along its opposite sides, a substantially U-shaped loop-member having opposite parallel legs slideable in said bearings, one of said legs being relatively short to adapt it to be released from its bearing, a detent on the longer leg of the loop-member, and a latch pivoted at one side of the main member to adapt it to fold across said member and having a hook adapted to snap over the longer leg of the loop-member in engagement with its detent to prevent said loop-member from being slid outwardly to release its shorter leg from its bearing on the main member.

2. A key-holder comprising a main member provided with opposite parallel spaced tubular bearings, a substantially U-shaped loop-member having opposite parallel legs slideable in said bearings, one of said legs being relatively short to adapt it to be released from its bearing when said loop-member is slid outwardly in the opposite bearing, a boss on the longer leg of the loop-member located between two of the spaced bearings, and a latch pivoted on the main member to adapt it to fold across said member and formed with a hook at its opposite end adapted to snap around the longer leg of the loop-member with its lateral edge in abutting engagement with the boss to prevent said loop-member from sliding in the main member.

3. A key-holder comprising a sheet-metal main plate-like member of substantially rectangular shape having pairs of tubular bearings on its opposite sides, a U-shaped wire loop-member having opposite parallel legs slideable in said bearings, one of said legs being relatively short to adapt it to be released from its bearing when said loop-member is slid outwardly in the opposite bearing, an abutment on the longer leg of said loop-member located between the ends of the bearings of one pair, and a latch pivoted between the bearings of the opposite pair to adapt it to fold across the main member and provided with an arcuate portion engageable around the longer leg of the loop-member with

its lateral edge in engagement with the side of the abutment to prevent the loop-member from being slid in its bearings outwardly with respect to the main member.

4. A key-holder comprising a central member of substantially rectangular shape having spaced-apart bearings on its opposite sides, a U-shaped wire loop-member having parallel legs fixedly held in certain of said bearings, a second U-shaped wire loop-member having its legs 10 slidable in certain of the bearings, one of said legs being relatively short to adapt it to be released from its bearing, an abutment on the longer leg of said slidable loop-member, and a latch pivoted to one of the legs of the fixedly held loop-member in the space between the bearings at one side of the central member, said latch formed with a hook at its opposite end adapted to snap over the longer leg of the slidable loop-member in engagement with the abutment thereon to lock said slidable loop-member from sliding in its bearings on the central member.

5. A key-holder comprising a central member provided with pairs of parallel spaced-apart bearings on its opposite sides, a substantially U-shaped wire loop-member having parallel legs held in the bearings at one end of the central member with one leg extending into a bearing at the opposite end of said central member and fixedly secured in said bearings, a slidable U-shaped wire loop-member having one leg extending through a bearing at one end of the central member and into the bearing at its op-

posite end and a shorter leg adapted to project into the opposite bearing at one end of the central member, an abutment on said longer leg of the slidable loop-member, and a latch having a bearing enclosing the longer leg of the fixed loop-member between the bearings at one side of the central member and formed with a hook adapted to snap around the longer leg of the slidable loop-member in engagement with its abutment to prevent said slidable loop-member from being withdrawn from the central member to release its shorter leg from its bearing thereon.

6. A key-holder comprising a central member of substantially rectangular shape having tubular bearings on its opposite sides, a loop-member fixedly secured in certain of said bearings at one end of the central member to adapt it for attachment to a suspension chain, a releasable U-shaped loop-member having its legs 15 slidable in certain of the bearings on the central member with one of said legs relatively short to adapt it to be disengaged from its bearing, a detent on the longer leg of the releasable loop-member, and a clasp pivoted to the central member and adapted to engage the detent means on the releasable loop-member to prevent the latter from sliding in its bearings, said releasable loop-member being adapted to be slid longitudinally of its bearings to release its shorter leg to permit 20 it to be rotated whereof to engage it with the end loops of a chain for holding a collection of keys strung thereon.

ARTHUR H. LEVESQUE.
